UNITED STATES PATENT OFFICE

129,257

DESIGN FOR A COMBINED STIRRER AND PICK

Lloyd J. Ganger, Richmond Hill, N. Y.

Application July 16, 1941, Serial No. 102,184

Term of patent 3½ years

To all whom it may concern:

Be it known that I, Lloyd J. Ganger, a citizen of the United States, residing at Richmond Hill, Long Island, in the county of Queens and State of New York, have invented a new, original, and ornamental Design for a Combined Stirrer and Pick, of which the following is a specification, reference being had to the accompanying drawing, forming part thereof, wherein:

The opposite side of the article illustrated in Figure 1 is substantially the same as the side shown.

I claim:

The ornamental design for a combined stirrer and pick, substantially as shown and described.

LLOYD J. GANGER.
